UNITED STATES PATENT OFFICE

CLIFFORD L. SNYDER, OF DETROIT, MICHIGAN, ASSIGNOR TO THE EVANS AUTO LOAD-
ING CO., INC., OF DETROIT, MICHIGAN

DECKING DEVICE

Application filed October 22, 1929. Serial No. 401,583.

This invention has relation to decking devices for loading automobiles or the like on freight cars, and particularly to devices of the type in which the brace members and other parts are made of metallic tubing, the loading device including a head to which the braces are pivotally attached, and which is constructed and adapted to reduce the temporary hub caps which are mounted on the hubs for the purposes of loading or decking the vehicle.

The present invention has relation principally to the head above mentioned and to the means whereby the braces are attached thereto, the object being to provide means whereby the device may be folded into a convenient and compact form for return to the shipper after use in the conveyance of vehicles to distant points.

20 The invention with the stated objects in view consists in the novel construction and combination of elements as hereinafter specifically described and set forth in the claims.

In the accompanying drawings illustrating a preferred embodiment of the invention,

Figure 1 is a plan view of the decking device in assembled form;

Figure 2 is a side elevation of the same, arranged within a freight car;

Figure 3 is a front elevation of the same;

Figure 4 is a front view representing the device in knocked down or folded condition;

Figure 5 consists of several views in perspective of the several elements constituting the head;

Figure 6 is a vertical central section of the head, with other parts attached; and

Figure 7 is a horizontal sectional view of the head with brackets to which the diagonal braces of the device are pivoted.

The head designated by the numeral 2 is in the form of a tubular casting of malleable metal, made integral with the inclined nipple 3, the circular side bosses or nipples 4 and the U-shaped flanged side bearings 5, which project beyond and are of smaller diameter at their semi-circular portions than the edges of the bosses or nipples 4. These side nipples 50 are provided for the insertion of the circular

discs 5' having each a projecting horizontal lug 7, pierced at its end for the reception of a pivot bolt 9, by which the horizontal braces 10 are attached to the lug, said braces being of tubular form as shown.

The numeral 11 designates the hub support, which is in the form of a cap having an enlarged cored out end forming a socket 12 screw threaded interiorly to match the screw thread on the hub, on which the holder is mounted on removal of the usual hub cap. This holder is of cylindrical form and is square shouldered at 13 to shut against the end of the head 2, the holder being formed with a cylindrical extension 14 which fits 65 within the bore of the head 2, and which is formed with a longitudinal slot 15 which by means of a bolt 16 and nut 17 allows for the adjustment of the hub support, and for securing the head and holder together. The 70 inner end of the threaded socket 12 is shaped to seat the end of the hub.

In loading and decking an automobile the hub caps are removed and the hub support 11 threaded tightly thereon. The automobile 75 is then raised to the desired level and the wheels to be placed in the decks turned so that the slots in the hub supports will be at the upper sides thereof.

The deck is then placed in position by 80 sliding the horizontal portion of the head 2 over the outer end of the hub support and dropping the bolt 16 downwardly through the holes 19 and the slot 15 and securing it in position by means of the nut 17 on its 85 lower end. This slot allows slight horizontal play between the car and the deck.

The downwardly inclined tubular braces 22 which seat in the nipples 3 are now placed snugly in position to support the load and 90 fastened to the floor of the freight car by means of the brackets 23 through which nails are driven for the purpose.

The side wall, tubular braces 10 are then 95 adjusted to an angular, divergent position, with their end brackets 24, pivotally attached thereto, said brackets being formed of T-shaped sections of metal having holes for the reception of nails to secure the brackets of the walls of the freight car. The center ribs 26

of these brackets are bored at intervals for the adjustment of the braces. The connected ends of the braces are bifurcated to embrace the ribs 26 and are connected thereto by removable bolts or pins 30. These braces may be arranged horizontally or above or below a horizontal plane. The braces 10 are bifurcated at their outer ends, and are pivotally connected to the lugs 7 of the discs 5. The 10 discs are seated in the ends of the nipples 4, behind the bearing parts 5, and the upper semicircular half bearing 5² fitted over the lower member 5. This arrangement forms a joint of universal character, the disk being 15 rotatable so that the braces 10 may be lowered down to the side of the main oblique brace 22 for packing and shipping purposes, and so that the braces 10 may be adjusted to any required height.

20 The brace 22 may be secured to the nipple 3 by a bolt or rivet 3'.

I claim:

1. A decking device for motor vehicles comprising a floor brace, a pair of wall braces, 25 and a head piece to which the braces are attached, said head piece constituting a support for the hub of the vehicle, and consisting of a tubular casting formed with an oblique nipple for the reception of the floor brace, 30 and with nipples at opposite sides for the connection of the wall braces, the latter being connected to the head piece by a universal joint, whereby the wall braces may be adjusted to different positions relatively to a horizontal plane.

2. A decking device of the character described, comprising a head piece of tubular form having nipples for the connection of floor and wall braces, said head piece having 40 a cylindrical bore, enlarged and interiorly threaded at one end for the reception of a hub cap and provided with means for the connection thereto of said hub cap.

3. A decking device according to claim 2, 45 and combined with a hub support slidably mounted thereon, said support being yieldable lengthwise and secured against longitudinal displacement.

4. A decking device according to claim 2, 50 and combined with a hub support slidably mounted thereon, said support being yieldable lengthwise and secured against longitudinal displacement, the hub support being formed with a slot, and connected to the decking head piece by a transverse bolt passing through said slot, and provided with a retaining nut.

5. A decking device of the character described, and comprising a tubular head piece 60 for the support of the hub cap, a nipple for the connection of an oblique floor brace, and lateral nipples having circular flanged sockets for the connection of horizontal wall braces.

65 6. The combination with the device recited

in claim 5, of wall braces, and wall brackets to which the braces are adjustably attached, said brackets being of T-shape in cross-section, and the center rib pierced at intervals for the reception of securing and adjusting bolts.

7. A decking device of the character described and comprising a tubular head piece with side nipples for the connection of wall braces, in combination with said braces, and disks jointedly connected to said braces, the 75 said nipples comprising a half circle bearing part for the disc and a detachable half circle member secured thereto, the said nipple forming a circular bearing for the disc and providing for the rotation of the latter.

8. A decking device of the character described, comprising a head piece of tubular form having nipples for the connection of floor and wall braces, said head piece having 85 a cylindrical base for the reception of a part of an automobile and combined with a hub support slidably mounted therein, said support being enlarged and interiorly threaded at one end for the reception of a hub.

9. A decking device according to claim 8, 90 with said hub support being yieldable lengthwise and secured against longitudinal displacement.

10. A decking device of the character described, comprising a head piece of tubular form having nipples for the connection of floor and wall braces, said head piece having 95 a cylindrical base for the reception of a part of an automobile, and combined with a hub support slidably mounted therein, said support being enlarged and interiorly threaded at one end for the reception of a hub, with 100 said hub support being yieldable lengthwise and secured against longitudinal displacement and formed with a slot, and connected to the decking head piece by a transverse retaining member passing through said slot, and detachably engaged with said head piece.

11. A decking device for motor vehicles 105 comprising supporting structures embodying head elements with which parts of a motor vehicle are engaged, and said head elements being constructed to permit limited movements of the vehicle in a horizontal direction 110 relative thereto, the supporting structure including floor and wall braces attached to the head elements and universal connections between the head element and wall braces 115 whereby the wall braces may be anchored at different elevations and angles and be foldable adjacent the floor brace.

12. A decking device for motor vehicles 120 comprising supporting structures embodying head elements with which parts of a motor vehicle are engaged, each head element including a pair of members assembled to permit limited movement of one member relative to the other, the supporting structure 125 including floor and wall braces attached to 130

the head element and universal connections
between the head element and wall braces
whereby the wall braces may be anchored at
different elevations and angles and be fold-
able adjacent the floor brace.

In testimony whereof I affix my signature.

CLIFFORD L. SNYDER.
